SPOON OR SIMILAR ARTICLE

James Russell Price, Esmond, R.I., assignor to Gorham,
Division of Textron Inc., Providence, R.I.

Continuation-in-part of design application Ser. No. 19,081,
Sept. 10, 1969. This application Aug. 4, 1970, Ser.
No. 24,305

Term of patent 14 years

Int. Cl. D7—03

U.S. Cl. D54—12

FIG. 1

FIG. 2

FIG. 3

FIG. 4

FIG. 5

FIG. 6

FIG. 7

FIG. 1 is a top plan view of the spoon,
FIG. 2 is a front elevational view thereof,
FIG. 3 is a right side elevational view thereof,
FIG. 4 is a rear elevational view thereof,
FIG. 5 is a left side elevational view thereof,
FIG. 6 is a bottom plan view thereof, and
FIG. 7 is an enlarged cross-section taken along line
7—7 of FIG. 2.

The design is intended for use on sets comprising forks,
spoons, knives, and similar articles of flatware.

This is a continuation-in-part of design application Ser.
No. 19,081, filed Sept. 10, 1969, and now abandoned.

I claim:

The ornamental design for a spoon or similar article, as
shown and described.
